(57) **CLAIM**

The ornamental design for a combined rear window and support for a soft top vehicle, as shown and described.

DESCRIPTION

FIG. 1 is a perspective view of a combined rear window and support for a soft top vehicle, showing our new design. The broken line structure is included for the purpose of showing the design in a position of use attached to a vehicle and forms no part of the claimed design;

FIG. 2 is a perspective view of the combined rear window and support for a soft top vehicle of FIG. 1;

FIG. 3 is a top plan view thereof;

FIG. 4 is a front elevation view thereof;

FIG. 5 is a left side elevation view thereof;

FIG. 6 is a right side elevation view thereof;

FIG. 7 is a rear elevation view thereof; and,

FIG. 8 is a bottom plan view thereof.
